ELECTRIC SWITCH

Emil J. De Noyers, Pittsfield, Mass., assignor to General Electric Company, a corporation of New York

Application October 15, 1953, Serial No. 386,157

3 Claims. (Cl. 200—16)

This invention relates to electric switches and more particularly to improvements in switches of the type in which a common contact makes selective engagement with a plurality of relatively fixed contacts.

A switch of the type used in connection with the present invention is disclosed and claimed in Minneci Patent 2,418,363, assigned to the same assignee as the present application. The Minneci patent was directed to an in-linetype switch in which solid insulation was introduced between the movable contact assembly and all of the fixed contacts, except the particular fixed contact with which the movable contact was in engagement and in which the creepage distance along the solid insulation was automatically made so that it was substantially proportional to the voltage difference between any fixed contact and the movable contact assembly. The Minneci structure comprised a plurality of fixed contacts supported in a straight line and adapted to be connected to points in an electrical winding having progressively increasing voltage, a movable contact assembly for successively engaging the fixed contacts, the movable contact assembly including electrical conducting means extending generally parallel to the line of the relatively fixed contacts and spaced therefrom, a pair of concentric insulating cylinders having oppositely extending oblique slots and being free to rotate, and a movable contact member extending through the slots and attached to the conducting means extending generally parallel to the aligned fixed contacts.

The Minneci type switch is useful as a tap changer for multitap windings such as the windings of a reactor or a transformer. In fabricating a switch of this type some difficulty has been experienced in mounting the movable contact assembly inside the rotatable cylinders with the contacting portion extending through the diamond-shaped aperture formed at the crossover point of the oblique slides. Therefore, it is an object of the present invention to provide a movable contact which will simplify assembling operations on a Minneci type switch.

It is another object of the invention to provide a Minneci switch having a movable contact which can be readily positioned on the interior of a small-sized rotatable cylinder.

Other objects will be apparent from the specification and drawing wherein Fig. 1 is a front elevation partly in section illustrating a movable contact in accordance with this invention mounted in place on a Minneci switch; Fig. 2 is a view of the rotatable cylinders of the switch of Fig. 1 showing the movable contact extending through the aperture formed at the crossover point of the oblique slots in the cylinder walls; Fig. 3 is an enlargement of the movable contact portion of the switch illustrated in Fig. 1; Fig. 4 is a view taken along the line 4—4 of Fig. 3; Fig. 5 is a view similar to Fig. 4 showing the contact fingers in the retracted position they would occupy prior to assembly; and Fig. 6 is a view taken along the line 6—6 of Fig. 4.

Briefly stated, in accordance with one of its aspects, this invention is directed toward an extendable contact

2

assembly comprising an elongated member having a pair of oppositely spaced grooves, means for mounting the member on a threaded shaft, a centrally slotted contact finger having a contact in position in each of the grooves, 5 the contact fingers being of a length about equal to the elongated member and being movable through the grooves of the elongated member, the contact finger slots being in register and having a depression adapted to seat a washer at the end of each slot opposite the contact end of the finger, a pin mounted on the elongated member and extending transversely outward from the contact fingers through the slots, a washer on each end of the pin in engagement with a contact finger, and a spiral compression spring mounted on each end of the pin, each spring 15 bearing against its associated washer to impart clamping action to the contact fingers and seat the washer in their respective depressions when the contact fingers are in an extended position.

The switch illustrated in Fig. 1 comprises a pair of end plates 10 and 11 which are held apart by members 12 and 13. The member 12 is preferably of insulation which may be a cylinder of synthetic resin bonded laminated insulating material and the member 13 is preferably made of metal so as to be an electrical conductor extending 25 through the bottom plate 11 so as to form the common terminal of the switch. Extending transversely through the insulating cylinder 12 are a plurality of insulating members 14 which may also be of synthetic resin bonded laminated insulating material and which carry on their 30 left-hand ends metal contacts 15 which are connected respectively to cables 16 which may lead to different taps on a winding (not shown).

For making selective contact with the fixed contacts 15 there is a movable contact assembly 17 threaded directly 35 on a screw shaft 18 or on a traveling screw (not shown) mounted upon the screw shaft 18. The threaded screw shaft 18 is rotated by a wheel 19 mounted outside the end plate 10. The wheel 19 may be a gear rotated by another gear (not shown). The movable contact assembly 17 makes sliding engagement with the conductor member 13. Other parts of the movable contact assembly 17 will be described in more detail hereinafter.

For insulating the conducting parts of the movable contact assembly 17 from the fixed contacts 15 the parts are surrounded by a pair of concentric insulating cylinders 45 21 and 22 which may also be made of synthetic resin bonded laminated insulating material. These are provided with oblique slots 23 and 24, respectively, extending in opposite directions these slots being just wide enough 50 to allow the contact fingers of the movable switch assembly 17 to pass therethrough.

The entire switch assembly may be submerged in insulating fluid, such as mineral oil or askarel, which often fills or substantially fills the tank of a high voltage transformer. If so, it will be understood that the liquid will 55 fill the cylinders 21 and 22.

Referring particularly to Figs. 3-6, the structure of the movable contact assembly 17 will now be described. An elongated body portion 26 adapted to engage the conductor 60 13 and to be moved in a lateral direction by the threaded shaft 18 has a pair of oppositely disposed grooves in which are positioned a pair of contact fingers 27 and 28. The contact fingers 27 and 28 have an extendable contact end adapted to make clamping engagement with the stationary contacts 15. The contact fingers 27 and 28 are maintained in sliding engagement with the grooves in the body portion 26 by means of a pin 29 mounted so as to pass through the body section 26 and also through longitudinal slots centrally disposed in the contact fingers 27 and 28. The exterior end of the finger slots most removed from the contact end has a depression adapted to seat a washer. Mounted upon the pin 29 are a spiral

biasing spring 31 positioned between a retaining washer 32 fixedly positioned by a cotter pin 33 and movable washer 34 bearing against the contact finger 27 to exert clamping pressure thereon. A similar assembly for the contact finger 28 comprises the spiral spring 35, washer 36, cotter pin 37 and washer 38.

Prior to assembly on the switch illustrated in Fig. 1 the movable contact assembly 17 is in the retracted form illustrated in Fig. 5. In this form it can readily be inserted inside the cylinder 22 and positioned in line with the diamond-shaped opening at the crossover point of the oblique slots in the cylinders. The contact fingers 27 and 28 are then extended through the opening until the washers 34 and 38 engage and are seated upon the depressions at the end of the contact finger slots. This locks the contact fingers in extended position and the mounting of the movable contact assembly 17 on the switch is complete.

With the contact assembly 17 in position on the switch illustrated in Fig. 1 it will be seen that the distance between the slots at the bottom of the cylinders is a maximum, and, as the voltage of the metallic parts of the movable contact assembly 17 corresponds to the voltage of the top fixed contact 15, the voltage between the movable contact assembly 17 and the lowermost fixed contact 15 will be a maximum. The creepage path between the lowermost stationary contact 15 and the metallic elements of the contact assembly 17 which extends through the annular space between the cylinders 21 and 22, is then very long in comparison with the straight line distance between these metallic elements. The horizontal distance between the slots gets less and less as the vertical distance to the movable contact is decreased but as the voltage difference between the movable contact and any fixed contact is proportional to the vertical distance between them, the effective insulation and creepage distance is proportional to the voltage stress.

While there has been shown and described a particular embodiment of this invention it will be understood by those skilled in the art that various changes and modifications can be made therein without departing from the invention; therefore, it is aimed in the appended claims to cover all such changes and modifications as fall within the true spirit and scope of the invention.

What I claim as new and desire to secure by Letters Patent of the United States is:

1. A switch comprising, in combination, a plurality of relatively fixed contacts insulatively supported in a straight line and adapted to be connected respectively to points in an electrical winding having progressively increasing voltage, a movable contact assembly for successively engaging said fixed contacts, said movable contact assembly including electrical conducting means extending generally parallel to the line of said relatively fixed contacts and spaced therefrom, a pair of concentric insulating cylinders surrounding said last-mentioned means and having oppositely extending oblique slots, said cylinders being free to rotate, and a contact member extending through said slots, and having axial movement through

said cylinders, said contact member having an elongated body portion in engagement with said conducting means which extends generally parallel to said aligned fixed contacts, a pair of oppositely disposed longitudinal grooves in said body portion, a clamping contact finger positioned in each groove and having longitudinal movement with respect thereto, each of said fingers having a contacting end and centrally positioned longitudinal slot, said slots being in register, the end of each slot opposite the contacting end having a circular impression adapted to seat a washer, a pin extending through the slots, a pair of washers mounted on said pin and in engagement with the contact fingers, and a pair of spiral biasing springs mounted on said pin and bearing against said washers whereby clamping action is exerted on said contact fingers and they are locked in extended position when said washers are seated in said circular impressions.

2. A clamping contact assembly adapted for assembling in a narrow space comprising an elongated body section, means for mounting said body section upon a conductor, a pair of oppositely disposed longitudinal grooves in said body section, a clamping contact finger having a contact end in each groove, said fingers being movable along said grooves, a longitudinal slot centrally positioned in each contact finger, said slots being in register, a circular depression adapted to seat a washer at the end of each longitudinal slot opposite the contact end of said finger, a pin extending through said slots and transversely outward on both sides of said body section, a washer mounted on said pin from each end in engagement with a finger, and a biasing spring mounted on each end of said pin, said biasing springs exerting pressure against said washers whereby said fingers are subjected to clamping action and are held in extended position with respect to said body section when said washers become seated in their respective depressions.

3. An extendable contact assembly comprising an elongated member having a pair of oppositely spaced grooves, means for mounting said member on a screw shaft, a centrally slotted contact finger having a contact end positioned in each of said grooves, said contact fingers being of a length about equal to said elongated member and being movable through said grooves, said slots being in register, a depression adapted to seat a washer at the end of each slot opposite the contact end of said finger, a pin mounted on said elongated member and extending transversely outward on both sides through said slots, a washer at each end of said pin in engagement with a contact finger, and a spiral compression spring mounted on each end of said pin, each spring bearing against its associated washer to impart clamping action to said fingers and seat said washers in their respective depressions when said fingers are in an extended position.
